UNITED STATES PATENT OFFICE.

MELVIN L. DAVIS AND GLEN W. COOK, OF ENID, OKLAHOMA, ASSIGNORS OF ONE THIRD TO HERBERT H. CHAMPLIN, OF ENID, OKLAHOMA.

PRESSURE-CONTROLLED CUT-OFF.

1,423,403.

Specification of Letters Patent. Patented July 18, 1922.

Application filed February 6, 1920. Serial No. 356,776.

To all whom it may concern:

Be it known that we, MELVIN L. DAVIS and GLEN W. COOK, citizens of the United States, and residents of Enid, in the county 5 of Garfield and State of Oklahoma, have invented certain new and useful Improvements in Pressure-Controlled Cut-Offs, of which the following is a specification.

Our invention relates to improvements in 10 automatic cut-offs, and it consists in the constructions, combinations and arrangements herein described and claimed.

One of the foremost objects of our invention is to provide a cut-off adapted more 15 particularly for use in connection with gas stoves, gas-lighting systems and the like, automatically cutting off the flow of gas when it falls below a predetermined pressure, and becoming locked in the cut off position 20 so as to temporarily prevent the gas from flowing into the pipes of the stove or lighting system when the pressure returns.

A further object of our invention is to provide automatic cut-off means for use in 25 connection with gas lighting systems, to prevent the asphyxiation of persons in a dwelling under the circumstance of the fall of pressure to a predetermined low point at 30 which the lights go out, and the consequent escape of gas into the room upon the return of the pressure.

A further object of the invention is to provide novel locking means to be used in 35 connection with a cut-off of the character described, which prevents the raising of a certain gas valve when the pressure returns after having fallen below a predetermined low point.

A further object of the invention is to 40 provide an automatic cut-off for gas lighting systems, gas heating systems, etc., which will positively prevent explosions in cases where a match is struck after a fall of the 45 gas pressure and the consequent escape of some of the fumes into the rooms of a dwelling.

Other objects and advantages will appear 50 in the following specification, reference being had to the accompanying drawings, in

which:

Figure 1 is a central longitudinal section

through the casing of the cut-off, illustrating the main valve in the open position as when the gas flows under normal pressure,

Figure 2 is a plan view of the cut-off 55 mechanism, the casing being shown in section;

Figure 3 is a detail cross section taken substantially on the line 3—3 of Figure 1,

Figure 4 is a detail cross section taken 60 substantially on the line 4—4 of Figure 2, but illustrating the locking mechanism engaged as when the main valve has fallen to the dotted line closed position under a reduction of gas pressure,

Figure 5 is a similar view illustrating 65 how the cam operates to lift the dog when the main valve is again lifted by manually turning the crank on the outside,

Figure 6 is a horizontal section taken substantially on the line 6—6 of Figure 4,

Figure 7 is a slight modification of the 70 gas inlet tube, illustrating the use of a glass or other non-corrosive bushing to prevent sticking of the inlet plunger valve, and

Figure 8 is a further modification in the 75 construction of the gas inlet tube, adapted for the same purpose.

In carrying out our invention we provide a gas-tight casing 1 which has gas inlet and 80 outlet pipes 2, 3. These pipes are respectively connected to the source of gas supply and to the connection which leads to the meter, in other words, this improved gas cut-off is disposed between the gas supply 85 and the device with which it is to be used in connection as for example, a lighting system or a gas stove, so that when the pressure of the gas in the main falls below a predetermined point, the flow or communication 90 is entirely cut off and can be resumed only by manual operation of the cut-off at a later time.

Assume the mechanism to be in the position when gas is flowing under normal pressure. The primary valve or plunger 4 in the inlet pipe 2 will then be in the position in Figure 1, at which time the ports 5, 6 are in registration, and gas flows into the casing 1, as indicated by the arrow. Under such 100 circumstances, the main valve 7 is in the full line position, so that the gas can in turn

flow into the throat 8 of the outlet pipe 3, and from there into the stove, lighting system, etc.

A rack 9, in extension of the plunger or primary valve 4, meshes with a gear 10 mounted on a counter-shaft 11 between the sides of the frame 12. An idler 13 connects the gear 10 with the gear segment 14 of the valve stem 15, to the extremity of which the main valve 7 is pivotally mounted as shown. The axial mounting 16 of the valve stem 15 is altogether independent of the manual revoluble or re-setting shaft 17 which appears directly below the axis 16.

The smooth portion of the rack 9 extends into the cylinder 18, where it is provided with a piston 19 against which the spring 20 presses. The tension of the spring 20 is adjustable by means of the follower 21 and set screw 22. Guide means 23 is also employed in connection with the rack and piston 19, such guide means being solely for the purpose of preventing turning of the valve 4 and consequent distortion of the position of the rack 9.

When the pressure of the gas against the plunger or valve 4 reaches a predetermined low point, the spring 20 shifts all of the connected parts toward the left so that the ports 5, 6 are moved out of registration and the flow of gas into the casing 1 stopped. The same movement of the valve 4 effects the main valve 7 which is thus caused to move into the dotted line position in Figure 1, by virtue of the operation of the train of gears illustrated. The valve 7 seats itself upon the rubber bushing 24 so that a gas-tight joint is made and no gas can escape into the outlet pipe 3.

Now consider Figure 4. The turning of the gear 10 in the clockwise direction of the arrow *a* in Figure 4, causes the gear 25 on the shaft 11 to turn in the same direction, because it is fixed on the shaft, thereby causing the gear 26, loose on the re-setting shaft 17, to move in the counter-clockwise direction of the arrow *b* in Figure 4 and cause the locking notch 27 of the locking boss 28 to move beneath the heel of the dog 29 and thus prevent counter rotation of the gear train by the return of the gas pressure against the head of the primary inlet valve 4.

The dog 29 is loosely mounted on the counter shaft 11, and the end thereof falls into the locking notch 27 by gravity. It is now absolutely impossible for gas to enter the outlet pipe 3 from the casing 1, because the main valve 7 is firmly seated on the bushing 24, and is furthermore locked in this position by reason of the engagement of the dog 29 with the locking boss 28. The boss 28 is a part of the gear 26.

Assume now that the gas pressure has re-

turned and the occupant of the house desires to re-open the cut-off so that the flow of gas may be resumed. He moves the crank 30, on the exposed end of the resetting shaft 17, in the direction of the arrow 31, which is suitably inscribed on the outside of the casing, thereby moving the lifting cam 32 beneath the dog 29 and raising the dog out of the notch 27. The re-setting shaft 17 is loosely mounted between the frame 12 and the packing gland 33 where the shaft passes through the casing. It has been explained that the gear 26 is loose on this shaft, and it naturally follows that the rotation of the shaft, as just explained, has no turning effect on the gear 26, until the finger 34 engages the lug 35 on the gear 26, whereupon continued rotation of the shaft causes the rotation of the gear in the direction counter to the arrow *b* in Figure 4.

The cam 32 overlaps the locking boss 28 of the gear 26, so as to easily come beneath the dog 29. This is illustrated in Figure 6. Access to the interior of the casing 1 for purposes of inspection and repairs, is had through the removable cover plate 36 at one side.

This plate is secured by thumb screws 37, which when screwed down, firmly bind the periphery of the plate 36 against a suitable bushing or packing 38 around the opening. It is to be observed that there is room for considerable modifications so far as the means of mounting the plate 36 is concerned. The construction and shape of the casing 1 is also subject to considerable modification, because obviously, these will be such as to more conveniently adapt the device to actual practice.

It should also be observed that there is a spring connection 39 between the re-setting shaft 17, and the frame 12. This spring operates to keep the shaft 17 in a normal position at which time the crank 30 on the outside will preferably extend downwardly.

Attention is now directed to Figures 7 and 8. In Figure 7, the inlet pipe 2^a has a bushing 40 of glass or other non-corrosive material, for the purpose of overcoming the danger of the primary valve 4^a sticking by a possible accumulation of sediment such as might occur in cases where the valves have no occasions to close for a long time. The glass bushing 40 will prevent rusting of the tube 2^a.

The form in Figure 8 is even better adapted to the prevention of the operation of the valve 4^b by the accumulation of sediment in front of it. Here the inlet tube or pipe 2^b is counter-bored at 41 so as to provide an annular space into which the valve 4^b projects. The resultant shoulder is considerably higher than an accumulation of sedi-

ment would ordinarily reach and therefore the possibility of the valve 4th sticking by this means, is entirely obviated.

We claim:

- 5 1. A cut-off, comprising a ported fluid inlet pipe, with a ported primary valve in normal registration therewith; tension-operated means opposing the fluid pressure against said valve but normally neutralized thereby, a fluid outlet pipe, and means operatively associated with a part of the primary valve, including a main valve for closing the outlet pipe by the influence of said tension means on the primary valve 10 when the fluid pressure reaches a predetermined low point.
- 15 2. A cut-off, comprising a ported fluid inlet pipe, with a ported primary valve in normal registration therewith; tension-operated means opposing the fluid pressure against said valve but normally neutralized thereby, a fluid outlet pipe, means operatively associated with a part of the primary valve, including a main valve for 20 closing the outlet pipe by the influence of said tension means on the primary valve when the fluid pressure reaches a predetermined low point, and means associated with said last named means for locking it and said main valve in the closed position and preventing the re-opening of the primary valve by the return of the fluid pressure.
- 25 3. Means for automatically cutting off the flow of gas when the pressure falls below a predetermined point, comprising a primary inlet valve held open by normal gas pressure, a gear train operatively combined therewith, a closure valve for an outlet pipe, normally 30 standing open but moved to the closing position by operation of the gear train when the primary valve closes upon fall of the sustaining gas pressure, and means operatively associated with said gear train for locking 35 the closure valve, including a locking disk and a gravity actuated dog.
- 40 4. An automatic gas cut-off including a primary inlet valve and a main outlet valve, with intermediate gear connections; and a manual re-setting shaft on which one of the gears is loosely mounted, with a cam for initially raising a dog in locking engagement with a notch in a boss on said gear, and a finger for subsequently engaging a lug on said 45 gear to obtain counter-rotation of the gear connection by continued turning of said shaft, and consequent re-opening of the primary and main valves.
- 50 5. An automatic gas cut-off, comprising a casing with a ported inlet pipe and an outlet pipe, an intermediate train having a counter-shaft mounted gear engaging a rack on a ported primary valve in the inlet, said rack having a piston in a cylinder which is engaged by an adjustable spring opposing 55 fluid under normal pressure, a valve stem, with a gear segment engaging an idler meshing with the first gear, including a valve normally raised from the ported outlet; and locking apparatus including a re-setting 60 shaft with a crank on the end exposed beyond the casing, with a cam for initially raising a dog when occupying a locking position in the notch of a boss on a gear loose on the re-setting shaft, said gear meshing 65 with a similar gear on the aforesaid counter-shaft, and a finger on the re-setting shaft subsequently engaging a lug on said loose gear to enable counter-turning of the gear train to re-open both valves after they have 70 moved to a closed position by the operation of the spring upon fall of the gas pressure.
- 75 6. An automatic cut-off, comprising inlet and outlet pipes, means exerting influence in line with reciprocating closure means associated with one pipe in opposition to fluid pressure thereagainst, and means revolved by the reciprocation of said closure means to in turn oscillate closure means of the other pipe into positions corresponding with those 80 of the first closure means.
- 85 7. In an automatic cut-off, revolute means associated with two closure means, one reciprocable the other oscillatable, whereby both operate simultaneously according to their kinds of movement; rocking means entering a locking engagement with a part of said associated means when the closure means assume predetermined positions, and revolute means for releasing said locking means.
- 90 8. In an automatic cut-off, revolute means associated with two closure means, one reciprocable the other oscillatable, whereby both operate simultaneously according to their kinds of movement; rocking means entering a locking engagement with a part of said associated means when the closure means assume predetermined positions, and means for releasing said locking means and operating said revolute means to re-open the closure means, including an actuating element primarily engaging the locking means, and members subsequently engaging for the operation of said 95 revolute means.
- 100 9. In a cut-off, means exerting pressure against a valve which opposes fluid in an inlet, and gears, including a segment which carries a main outlet valve, operated to close 105 an outlet by the closure of the inlet valve, and vice versa.
- 110 10. In a cut-off, means exerting pressure on an inlet valve which carries a rack, and

an outlet valve carried by a gear segment which is actuated by gears in mesh with the rack.

11. The combination in a cut-off, of a sliding inlet valve with a rack, gears revolved by the rack when the inlet valve closes, and a segment in mesh with the gears, which clap a main valve upon an uncovered outlet, and vice versa.

10 12. In a cut-off, an inlet valve having a rack, slid to a closed position by tension means, and guide means preventing turning

of the valve and consequent distortion of the position of the rack in respect to a gear which operates a main valve.

13. In a cut-off, an inlet valve having a rack, slid to a closed position by tension means which exerts pressure on a piston on the rack, and guide means carried by the piston, contacting the rack to prevent its turning in respect to a gear which operates a main valve.

MELVIN L. DAVIS.
